UNITED STATES PATENT OFFICE.

JOHN W. BRERETON, OF GLEN ALLEN, VIRGINIA.

DESIGN FOR A SPOON.

No. 38,680.

Specification for Design.

Patented July 16, 1907.

Application filed May 23, 1907. Serial No. 375,366. Term of patent 3½ years.

To all whom it may concern:

Be it known that I, JOHN W. BRERETON, a citizen of the United States, residing at Glen Allen, in the county of Henrico and State of Virginia, have invented a new, original, and ornamental Design for Spoons, of which the following is a specification, reference being had to the accompanying drawing, forming part thereof.

The figure is a plan view of a spoon, showing my new design.

I claim:

The ornamental design for a spoon, as shown.

JOHN W. BRERETON.

In the presence of—

L. T. W. MARYE,
GEORGE B. WHITE.
